Primary Examiner — Karen S Acker(74) *Attorney, Agent, or Firm* — Alleman Hall Creasman & Tuttle LLP(57) **CLAIM**

The ornamental design for a paper sheet, as shown and described.

DESCRIPTION

FIG. 1 is a front view of a paper sheet according to the new design.

FIG. 2 is a reference view thereof with denotations of the areas of enlarged detail shown in FIGS. 3-7.

FIG. 3 is an enlarged detail view of area 3 circumscribed within FIG. 2.

FIG. 4 is an enlarged detail view of area 4 circumscribed within FIG. 2.

FIG. 5 is an enlarged detail view of area 5 circumscribed within FIG. 2.

FIG. 6 is an enlarged detail view of area 6 circumscribed within FIG. 2; and,

FIG. 7 is an enlarged detail view of area 7 circumscribed within FIG. 2.

The cross-hatching depicts contrast in specific areas of the drawings. The dotted lines in the drawings illustrate fold lines. The dot dash dot broken lines denote the detail areas and form no part of the claimed design.
